CLAIM

The ornamental design for a cleaning implement, as shown and described.

DESCRIPTION

FIG. 1 is a perspective view of a cleaning implement, embodying the new design;

FIG. 2 is a front elevational view of the cleaning implement of FIG. 1;

FIG. 3 is a rear elevational view of the cleaning implement of FIG. 1;

FIG. 4 is a right elevational view of the cleaning implement of FIG. 1;

FIG. 5 is a left elevational view of the cleaning implement of FIG. 1;

FIG. 6 is a top planar view of the cleaning implement of FIG. 1; and,

FIG. 7 is a bottom planar view of the cleaning implement of FIG. 1.

The broken lines shown in the drawings are for illustrative purposes only and form no part of the claimed design.
